UNITED STATES PATENT OFFICE.

IRA EDWARD SMITH, OF STOCKTON, CALIFORNIA.

INITIAL OIL-HEATING MEANS FOR OIL BURNERS.

Application filed October 27, 1925. Serial No. 65,064.

This invention relates to improvements in oil burners and particularly to a means for applying initial heat to the oil as delivered to the nozzle or burner plate, in order to enable such oil to be more readily ignited than is the case otherwise. This is desirable with the more or less heavy and non-volatile fuel oils which are used in connection with oil burners.

10 In all such burners as far as I am aware, such initial heating, if any, is had by means of a gas flame or the like. Either such gas must be lit every time it is wanted, which is inconvenient, or else a continuously lit pilot 15 light must be provided, which is of course a continuous source of expense.

The principal object of my invention therefore is to provide for heating the oil by means of electricity in such a manner that 20 the current is only consumed when it is wanted, so that the expense of operation is negligible.

25 The structure is extremely simple, is very inexpensive to manufacture and install and there are no parts to wear out or give trouble, so that there is no expense for upkeep.

30 A further object of the invention is to arrange the heating means so that it completely surrounds the burner member, and provides a localized heat just where it is wanted.

I particularly have in mind to apply this heating means in connection with a motor 35 driven oil burner of the rotary burner plate type, such as is shown in my Patent No. 1,512,247 dated October 21st, 1924, but it will be obvious from the following specification that its use and application is not limited 40 to such type of burner.

These objects I accomplish by means of such structure and relative arrangement of parts as will fully appear by a perusal of the following specification and claims.

45 In the drawings similar characters of reference indicate corresponding parts in the several views:

Fig. 1 is a sectional elevation of the burner casing showing the heating element 50 mounted in connection therewith.

Fig. 2 is a similar view taken on the line 2—2 of Fig. 1, showing the burner plate mounted in place in the casing.

55 Fig. 3 is a top plan view of the assembly with the upper casing member removed.

Referring now more particularly to the characters of reference on the drawings, the burner itself comprises essentially a perforated and dish shaped plate 1 which is mounted in connection with a driven sleeve 60 2 having a centrifugal fan 3 a certain distance below the plate. Also mounted in connection with the burner plate centrally thereof is a member 4 having a circumferential slit 5 to allow the oil to pass onto the 65 plate, the oil passing up into said member through the sleeve 2 and being thrown centrifugally with the rotation of the plate.

This structure is substantially the same as shown in my co-pending application for 70 patent, Serial No. 24,147 filed April 18th, 1925, except as to the exact form and arrangement of the burner plate hereinafter described.

Surrounding the plate and fan and extending above and below these parts is the burner casing. This casing preferably comprises three members; 6 the lower one; 7 the central portion and 8 the upper member. The members 6 and 8 are of metal while the 80 member 7 is of refractory material such as a good grade of porcelain, which is also a good electrical insulator.

The member 6 is substantially in the form of a flanged plate supporting the central 85 member 7, the contacting faces of said members having cooperating lugs and sockets as indicated at 9 to prevent rotative movement therebetween.

The member 7 is formed as a heavy cy- 90 lindrical ring, with its upper surface having an upward slope from its inner edge. This member supports the upper member 8, there being cooperating lugs and sockets in the contacting faces of these members as indicated at 10 to prevent relative rotative movement therebetween.

The member 8 is in the form of a bowl 100 with its bottom partly cut away, the remainder of the bottom portion A resting on top of the member 7 and having the same slope. The side of the member 8 extends upwardly for some distance and is disposed a short distance outwardly of the plane of the outer edge of the member 7.

105 My initial heating means is in the form of an annular band 11 which is supported by the member 7. This band is floatably mounted in the casing so that it can freely expand and contract with changing tempera- 110

ture conditions by means of lugs 12 fixed on the outer face of the band, from which lugs radial pins 13 project to seat in oversize sockets 13^a provided in the casing member 7.

The ends of the band are spaced but a short distance from each other as shown in Figs. 1 and 3, and separate terminal members 14 project outwardly from the ends of the band through the casing member 7 for some distance as to be well out of the zone of direct heat.

These terminals are preferably in the form of radial rods which form additional supporting means for the band and project through oversize orifices 14^a in the casing member 7. The band is so located that its upper edge is a short distance below the adjacent upper edge of the portion A of the bowl 8.

The band is preferably made of nichrome steel, this being a metal having high electrical resistance and of a nature to resist deterioration when subjected to high temperature.

In order to provide for the proper heating of the band when a current is passed therethrough, the band is cut away from its under edge between the different lugs and terminal members as shown in Fig. 1. This forms restricted areas in the length of the band which provide increased resistance to a current passed over such areas, so that these portions of the band become red hot, while those adjacent the terminals and lugs remain relatively cool.

The outer periphery of the plate 1 for the major portion of its length is concentric with the band, and is located so as to be slightly above the upper edge of the band, as shown in the left hand side of Fig. 2. The plate being dish shaped, any oil thereon and thrown centrifugally with the rotation of the plate is therefore delivered onto the member 8 rather than against the band.

Disposed about the rim of the plate at suitably spaced intervals and formed by depressing the metal is a plurality of small discharge troughs 15, which project outwardly of the rim somewhat as shown in Fig. 3, and terminate somewhat lower than the same as shown in Fig. 2, or so as to be practically in line with the heater band. Therefore with the rotation of the plate any oil in these troughs will be thrown directly against the band. The result is that while the majority of the oil clears the band, so that an undue cooling effect on said band is avoided and the same may retain its red heat, sufficient oil actually engages the band to cause such oil to be instantly ignited by the heated band. At the same time a zone all around the burner plate is heated, so that the oil not actually engaged with the band, and the air passing

up around the band and through the plate with the action of the fan is subjected to heat. Therefore the entire fuel mixture is heated, placing it in condition to be readily ignited, either by the oil ignited by contact with the band, or by additional and quicker operating ignition means.

The band being spaced from the casing element 7, not only enables the band and casing member to expand or contract without affecting each other, but enables the draft of air to pass upwardly on both sides of the band, so that the entire area of the band is available for air and oil heating purposes.

The contacting faces of the members 7 and 8 having a downward and inward slant, there is no possibility of any oil flowing down the surface A subsequently flowing between the members 7 and 8.

The circuit to the band 11 may be of a very simple nature, consisting essentially of leads 16 connected to the terminals 14 and extending to the power wires 17 with a switch 18 interposed in the leads.

If the heating means is incorporated in my particular form of oil burner however the switch would preferably be included as a part of the automatically operating furnace thermostat switch as shown in my co-pending application for patent, Serial No. 32901, filed May 26th, 1925.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. An initial oil heating means for oil burners comprising, with a burner member onto which the oil to be burned is delivered, an electric heating element surrounding and facing said member in spaced relation thereto and exposed to the oil.

2. An initial oil heating means for oil burners comprising, with a burner member onto which the oil to be burned is delivered, an electric heating element surrounding and facing said member in spaced relation thereto, and arranged in the form of an annular band disposed adjacent the plane of the outer edge of the burner member and having its inner periphery exposed to the oil.

3. An initial oil heating means for oil burners comprising, with a burner member onto which the oil to be burned is delivered,

and an insulation casing surrounding the member in spaced relation thereto; an electric heating element mounted in said casing to provide heat about said member in the plane of the outer edge of the burner member.

4. An initial oil heating means for oil burners comprising, with a burner member onto which the oil to be burned is delivered, 10 and an insulation casing surrounding the member in spaced relation thereto; an annular electric heating element in the form of a band, mounted adjacent the inner face of the casing and disposed adjacent the 15 plane of the outer edge of the burner member.

5. An initial oil heating means for oil burners comprising, with a burner member onto which the oil to be burned is delivered, 20 and an insulation casing surrounding the member in spaced relation thereto; an annular electric heating element in the form of a band, disposed inwardly of the casing and located adjacent the plane of the outer 25 edge of the burner member, and means supporting the band from the casing in a manner to allow of free expansion and contraction of the band.

6. An initial oil heating means for oil 30 burners comprising, with a burner member onto which the oil to be burned is delivered, and an insulation casing surrounding the member in spaced relation thereto; an annular electric heating element in the form of 35 a band, disposed inwardly of the casing and located adjacent the plane of the outer edge of the burner member, and pins projecting radially from the band and seating in relatively large sockets in the casing.

40 7. An initial oil heating means for oil burners comprising, with a burner member onto which the oil to be burned is delivered, and an insulation casing surrounding the member in spaced relation thereto; an annular electric heating element in the form 45 of a band, disposed inwardly of the casing in spaced relation thereto and supported thereby, the upper edge of said band being

adjacent the plane of the rim of the burner member. 50

8. An oil burner structure including a casing, a burner plate onto which oil to be burned is delivered turnably mounted within the casing in spaced relation thereto and located intermediate the top and bottom of the casing, a heating band mounted in the casing in spaced relation to the plate and located adjacent the plane of the rim of the plate, and means incorporated with the plate whereby when with the rotation 60 of said plate the oil is thrown centrifugally therefrom a small portion only of such oil will be thrown against the band. 65

9. An oil burner structure including a casing, a burner plate onto which oil to be 70 burned is delivered turnably mounted within the casing in spaced relation thereto and located intermediate the top and bottom of the casing, a heating band mounted in the casing in spaced relation to the plate and 75 located adjacent the plane of the rim of the plate, said rim being disposed above the upper edge of the band, and troughs depressed from said rim at spaced intervals; the outer edges of the troughs being disposed to cause oil thrown therefrom to contact with the band.

10. An initial oil heating means for oil 80 burners comprising, with a burner member onto which the oil to be burned is delivered, an insulation casing surrounding the member in spaced relation thereto; an annular electric heating element in the form of a band, whose ends are separated, disposed within the casing with its upper edge 85 adjacent the plane of the rim of the burner member, and terminal members projecting through the casing from the band adjacent the ends thereof; the band being reduced in width beyond the terminals, whereby said 90 reduced portions will become more highly heated than the remainder when a current is passed through the band.

In testimony whereof I affix my signature.

IRA EDWARD SMITH.
